VENDING MACHINE

Benjamin W. Fry and John Gottfried, St. Louis,
Mo., assignors to National Slug Rejectors, Inc.,
St. Louis, Mo., a corporation of Missouri

Application September 28, 1937, Serial No. 166,037

9 Claims. (Cl. 312—94)

This invention relates to vending or dispensing machines and contemplates an improved and simplified mechanism for individually supporting a stack of articles to be dispensed and effecting the delivery of such articles one at a time while adequately supporting the articles remaining in the machine and, as an incident to the delivery of an article, moving a second article into delivery position. The invention further contemplates improved and simplified devices for locking and dispensing mechanism when the machine is empty, for receiving the individual support of each article as it is delivered, and for utilizing these supports to prevent access to and tampering with the interior mechanism.

In the drawings:

Fig. 1 is a fragmentary side elevation of the dispensing mechanism, the case or housing being removed.

Fig. 2 is a fragmentary front elevation of the mechanism.

Fig. 3 is a fragmentary longitudinal section showing the machine in the operation of delivering an article.

Fig. 4 is a transverse sectional detail illustrating the means for locking the dispensing mechanism when the machine is empty.

Fig. 5 is a transverse section substantially on the line 5—5 of Fig. 1.

Fig. 6 is a fragmentary rear elevation.

Fig. 7 is a perspective of an article supporting shelf or tray.

The body of the machine may be conveniently formed of two angle plates 10 and 11 secured in a spaced relation by suitable means such as yokes 12. The webs of plates 10 and 11 form the side walls of a container which may be of considerable height and is adapted to receive, hold, and dispense articles in the manner to be described. The flanges 13 and 14 of the plates 10 and 11 respectively are secured together at suitable intervals by the yokes 12, there being a longitudinal slot 15 between the adjacent edges of the flanges. Substantially opposite the dispensing mechanism the slot 15 is widened into a slot 16 for a purpose to be hereinafter described. The front of the article container is open and is provided with suitably spaced supports 17 for the article holding trays or shelves. These supports may conveniently be wires of suitable diameter, say about 16 gauge, passed through apertures in the side walls 10 and 11, and bent off at each end to prevent their accidental removal. The supports 17 are located adjacent the free edges of the side walls 10 and 11 and are of relatively small transverse dimensions. They are adapted to receive and support the ends of article carrying trays or shelves, identified generally by the numeral 18, and preferably of the configuration illustrated in Fig. 7.

Each tray 18 comprises a flat shelf portion 19 having a free end 20 which is supported on the support 17. From the opposite end there projects in the plane of the sheet 19 a T shaped head 21. Depending from the same end is a spacing flange 22 which may comprise an aperture 23. Such trays may conveniently be formed from sheet stock by blanking out the aperture 23, leaving the T head 21 integral with the shelf 19 and thereafter bending the flange 22 downwardly to a position substantially at right angles to the shelf 19. The height of the flange 22 corresponds to the spacing of the supports 17 so that in the machine each tray except the lowermost is supported in front by a support 17 and 15 in the rear by the flange 22 resting upon the upper surface of the next tray below. The front edge of the lowermost tray is likewise held by a supporting wire 17 and its rear end is held by a part of the dispensing mechanism as follows:

The T head of each tray projects through the slot 15 between the flanges 13 and 14, the yoke formation of the connectors 12 providing clearance for these heads. The trays may thus move freely downwardly but are held by the engagement of the T heads 21 with the flanges 13 and 14 against horizontal movement. The T head 21 of the lowermost tray is supported on the transversely extending arm 24 of an escapement member pivoted at 25 to the plate 10. The escapement member comprises a second transversely extending arm 26 the upper margin of which is spaced from the upper margin of arm 24 by an amount slightly less than the depth of the tray flanges 22 and the spacing of the heads 21 of successive trays as determined thereby. Arm 24 is below the pivot 25 while arm 26 is above the pivot 25 and is located rearwardly from arm 24 by an amount such that in the normal position of the escapement member the T heads 21 clear the arm 26, passing between this arm and the flanges 13 and 14. The T head 21 of the lowermost tray rests upon the arm 24, this arm being located somewhat below the support 17 for the front end of the lowermost tray to facilitate the downward turning of the rear end of the tray incident to the dispensing operation. When the escapement member is rocked counter-clockwise (Fig. 1) about pivot 25, arm 26 swings beneath the head 21 of the second tray in the stack to temporarily support the entire stack of trays.

Immediately thereafter, arm 24 is, by the same movement, withdrawn from beneath the head 21 of the lowermost tray permitting this tray to fall. The front end of the lowermost tray is at this time held by its support 17 but the tray and the article thereon are free from all other articles and trays in the stack, the front end of each tray being held by its own support 17. As the rear end of the lowermost tray drops, its T head 60

21 passes out of the narrow slot 15 and into the slot 16 which is wide enough to clear the T head. The front end of the tray slides rearwardly off from the support 17 and its rear end is caught 5 by a supporting rod 27 extending transversely between the side walls 10 and 11. The flange of the tray forms a hook which insures its engagement and support upon the rod 27. The tray thereon pivots upon the rod 27 until its 10 front portion engages a second transverse rod 28 located near the front of the machine and substantially below the rod 27. The article upon the tray thus held in a forwardly and downwardly inclined position is thereupon delivered 15 from the front of the machine as shown in Fig. 3.

When the escapement member is restored to normal position, arm 26 is withdrawn from beneath the head 21 of the tray temporarily held thereon, and said head drops into contact with 20 arm 24, the front ends of each of the superposed trays dropping the same distance since each is supported upon the next tray below by its flange 22. Each tray being held against a forward movement by the engagement of its T head 21 25 in slot 15, the tilting of the trays thus effected is sufficient to cause the rear end of each to clear its supporting wire 17. The downward motion of the rear end of each tray being stopped by the engagement of the T head 21 of the 30 lowermost tray with arm 24, the trays pivot about their T heads, and the front end of each is engaged by the next supporting wire 17 below the one from which it was displaced. There is thus provided an effective means for individually supporting a stack of articles and downwardly displacing the support of each article as the lowermost article and its support are removed.

As the machine is repeatedly operated the empty trays accumulate upon the supporting rods 27 and 28, from which they may be removed and replaced in the top of the machine as desired. To prevent their unauthorized removal a latch 30 is pivoted on a bracket 31, secured to the side wall 10, and is urged inwardly through 40 a slot 32 in the side wall by suitable means such as a spring 33 into position above the trays held on the rods 27 and 28. The latch 30 is so located that if there are one or more empty trays 45 on the supporting rods 27 and 28, they cannot be lifted an amount sufficient to permit the flange 22 of the lowermost tray to clear the rod 27. Access to the interior of the container from the bottom (which is otherwise open) is thus prevented. Suitable means are provided for 50 placing the latch 30 to permit the removal of the trays when desired. These means may conveniently comprise a rod or wire 34 supported for vertical movement on the side wall 10, urged upwardly by means such as a spring 35 and 55 provided with a manipulative head 36. The lower end of wire 34 is adjacent the inner face of latch 30 and downward movement of the wire displaces the latch to clear the lateral margin of a tray or stack of trays on the supporting rods 27 and 28.

Any suitable mechanism may be provided for operating the escapement member in a manner heretofore described. The mechanism for this 60 purpose illustrated in the drawings comprises a plate 37 (with which plate the arms 24 and 26 are integral) disposed outside and parallel to the side wall 10, and provided with outwardly turned ears 38 and 39 between which ears there is 65 received an arm 40 projecting upwardly from a

horizontal disposed bar 41 suitably held for rectilinear movement on the side wall 10. Secured to the bar 41 is a full stroke ratchet plate 42 cooperating with a full stroke pawl 43 pivoted on the side wall 10 and controlled by a spring 44. 5 Likewise secured to bar 41 is the shank 45 of an operating handle 46. It will be apparent that a full outward movement of the operating handle 46 rocks the escapement member counterclockwise (Fig. 1), causing the delivery of an 10 article in the manner heretofore described, and that the restoration of operating handle 46 to normal position completes the repositioning of the remaining articles and trays, ready for a 15 subsequent operation as likewise above described. Obviously, any of a variety of spring means may be provided for restoring the operating handle and parts moved thereby to normal position after their displacement by pulling the operating handle outwardly. For example, a bail comprising 20 side arms 55 and connecting bar 56 may be pivoted in a bracket 59 secured to the side wall 11 or to a frame adapted to contain a number of units of the type herein described. To the bail may be attached one end of a spring 57, the 25 opposite end of which is secured to a bracket 58. The bar 56 of the bail stands in front of the full stroke plates 42 of one or more dispensing units. The forward movement of the operating handle thus stresses the spring 57 and the spring restores the operating handle and parts moved thereby to normal position when the handle is released.

Means are provided for locking the dispensing 30 mechanism against movement when the machine is empty. These means may conveniently comprise a latch for the bar 41 which is displaced to permit movement of this bar by the presence of a tray in article delivering position. The form of lock illustrated in the drawing comprises 35 a latch 47 pivoted on a bracket 48 secured to the side wall 10 and urged inwardly through a slot 49 in the side wall by a suitable spring such as 50 into position to be engaged by a tray held on the bar 24 and the lowermost supporting wire 17. If there is no tray in this position the latch is moved inwardly by its spring 50 and when so moved its latching nose 51 engages in a notch 52 in the bar 41, thereby locking the bar 41 and the entire dispensing mechanism against movement. It will be obvious that the invention is susceptible to embodiment in many forms other than the one selected and described herein by way of illustration, and the appended claims are to be construed as extending 55 to all such equivalent forms and devices.

What is claimed is:

1. A dispensing machine comprising a plurality of article receiving trays each provided adjacent one end thereof with guide means and spacing 60 means adjacent said guide means whereby each tray is supported from an adjacent tray, a container, counterpart guide means associated with said container, said first-named guide means and said counterpart guide means cooperating to permit vertical and pivotal movements of the trays while restraining horizontal movement thereof, individual supporting means for the opposite end of each of said trays associated with said container, article delivery means comprising 65 a support for the pivot end of the tray in article delivering position, means for withdrawing said support thereby permitting vertical movement of the pivot ends of all of said trays and the displacement of the opposite end of each of said 70 trays.

- trays from its support, means for stopping the vertical movement of the pivot ends of said trays when they have been displaced an amount substantially equal to their spacing, thereby effecting a pivotal movement of each of said trays to bring the opposite end thereof into engagement with the support adjacent the one from which it was displaced. 5
2. A dispensing machine comprising a container provided with a longitudinal slot, a plurality of trays adapted to be received in said container, each comprising a T shaped head adapted for engagement in said slot and a spacing flange adjacent said T shaped head by which one end of each tray except the lowermost is supported from the next tray below, individual supporting means for the opposite ends of each of said trays associated with said container, means for supporting the T shaped head of the lowermost tray, means for withdrawing said support and restoring said support when the adjacent ends of each of said trays has moved by an amount equal to the spacing of the trays, the construction and arrangement being such that said downward movement withdraws the opposite end of each of said trays from its support and the interruption of the downward movement causes said opposite end of each of said trays to come to rest upon that support adjacent the one from which it was displaced. 10
3. A dispensing machine comprising a container provided with a longitudinal slot, a plurality of article receiving trays adapted for insertion in said container, each of said trays comprising a T shaped head adapted for engagement in said slot, means for supporting the end of each of said trays opposite the T head thereof, spacing means for supporting the T head end of each tray, except the lowermost tray, upon the tray immediately beneath it, article delivery means comprising a support for the T head end of the lowermost tray, and means for withdrawing said support and simultaneously providing a support for the T head of the next tray, a widened slot in said container adjacent said article delivery means through which slot said T head may pass permitting the lowermost tray to drop to an article delivered position, and means for receiving and supporting said tray in said article delivered position. 15
4. A dispensing machine comprising a container provided with a plurality of individual supports each adapted to receive and support one end of an article receiving tray, means associated with said container, and terminating adjacent the lowermost tray for receiving and guiding the opposite end of each of said trays for vertical and pivotal movements, counterpart means associated with each of said trays for engagement by said guide means, spacing means associated with each of said trays adjacent said counterpart means whereby the adjacent end of each of said trays except the lowermost is supported by the tray immediately beneath it, article delivery means, and means associated with said article delivery means for supporting the pivot end of the lowermost tray, means for withdrawing such support of the pivot end of the lowermost tray to permit said tray to pivot about its opposite end and become disengaged from said guide means, means simultaneously moving into position to support the pivot end of the next tray, and means for stopping the downward movement of the pivot end of said disengaged tray affording a pivot upon which the tray rotates to a forwardly and downwardly inclined article delivered position. 20
5. A dispensing machine comprising a container, means associated with said container for individually supporting a plurality of article receiving trays, means for displacing said trays one at a time to effect the delivery of the article thereon, means for receiving the trays from which articles have been delivered and a latch for preventing the removal of said trays from said receiving means. 25
6. A dispensing machine comprising a container, means associated with said container for individually supporting one end of each of a plurality of article receiving trays, a plurality of trays adapted to be thus supported, means associated with the opposite end of each of said trays whereby each tray except the lowermost is supported from the tray immediately beneath it, article delivery mechanism comprising an escapement member, said escapement member comprising an arm adapted to support one end of the lowermost tray and a second arm adapted to temporarily support one end of the adjacent tray, means for shifting said escapement member to withdraw said support for the lowermost tray and to render said temporary support effective, and means for restoring said escapement member to normal position. 30
7. A dispensing machine comprising a container, a plurality of article receiving trays adapted to be held in said container in superposed relation, relatively immovable supports mounted on said container adapted each to hold one end of each of said trays, a movable support mounted on the container for the opposite end of the lowermost tray, and means for supporting the opposite end of each of said trays except the lowermost from the tray immediately below it. 35
8. In an article dispensing machine, a container comprising side plates having flanges bent off therefrom, a plurality of yokes secured to and holding said flanges in spaced relation to form a longitudinal slot; a plurality of trays in said container, each tray comprising an article supporting shelf, a flange bent off from said shelf for engagement with an adjacent tray, and a T head projecting from said shelf and through said container slot; spaced means on said container supporting the end of each tray opposite the T head thereof; article delivery means comprising a member normally supporting the T head of the lowermost tray, and means for temporarily engaging the head of the tray adjacent the lowermost and simultaneously withdrawing the support from the lowermost tray and permitting said tray to drop to article delivering position. 40
9. A dispensing device comprising a container, vertically spaced supporting means therein, a vertical stack of article-receiving trays, one edge of each tray being supported on one of said supporting means, means supporting the opposite edge of each tray upon the respective tray therebeneath, escapement means mounted in said container at the bottom of said stack, said escapement means being movable between two positions, in one of which it supports the opposite edge of the lowermost tray, and in the other of which it releases the lowermost tray from the stack and temporarily supports the opposite edge of the next uppermost tray. 45
